UNITED STATES PATENT OFFICE.

ALFRED M. MOORE, OF MALDEN, MASSACHUSETTS, ASSIGNOR TO ALFRED M. MOORE AND CHESTER M. MOORE, COPARTNERS, DOING BUSINESS UNDER THE NAME AND STYLE OF MOORE & COMPANY, OF EVERETT, MASSACHUSETTS.

WIRE-STITCHING MACHINE.

1,380,733.

Specification of Letters Patent. Patented June 7, 1921.

Application filed May 21, 1919. Serial No. 298,699.

To all whom it may concern:

Be it known that I, ALFRED M. MOORE, a citizen of the United States, and resident of Malden, county of Middlesex, and Commonwealth of Massachusetts, have invented an Improvement in Wire-Stitching Machines, of which the following description, in connection with the accompanying drawings, is a specification, like characters on the drawings representing like parts.

This invention relates to wire stitching or stapling machines and its object is to provide an improved construction for driving wire staples, and particularly in goods of non-staple penetrating nature such as metal, fiber, etc., i. e., goods which, on account of their hardness, have been previously provided with apertures to receive the staple.

This invention also relates to an improved form of reinforced shoe shank made by my novel construction above referred to and presently to be described.

Wire-stitching machines for applying wire thread or staples to paper, cloth, leather, etc., are commonly used in the arts, but they have, so far as I am aware no means for positively leading the staple legs to accurately predetermined points. It is impossible therefor to use them in connection with material hard enough to break the legs or shanks of the staple owing to the fact that such material must be previously provided with apertures and, unless the holes in the material are made much larger than is otherwise necessary, there is always danger that the staples will strike the edge of the material and be bent down upon the material or broken instead of being driven through and fastened upon it.

To avoid this difficulty I have invented a novel form of guide which leads the legs of the staple accurately to predetermined points on the work or into the previously prepared openings therefor.

In the drawings of one embodiment of my invention,

Figure 1 is a front view of a portion of the head of a conventional form of wire stitching machine equipped with my novel

thread or staple guide, other parts broken away;

Fig. 2, a side view thereof;

Fig. 3, a side view of my novel guide;

Fig. 4, a similar view with part of the side wall removed and showing certain parts behind the same;

Fig. 5, a view of the opposite side of the guide from that shown in Fig. 4; and

Fig. 6, a view of a reinforced shoe shank as stitched by my novel construction.

Referring first to Figs. 1, 2,— 1 is the depending head of the machine suitably suspended by parts not shown, and broken away.

This head is channeled on its front face, Fig. 1, see dotted lines, to receive a plunger 1', and, Fig. 2, carrying a hammer 2 at its lower end.

This plunger carries a cutter 3 at one side, Fig. 1, for severing the wire thread, as will be pointed out presently. Pivoted for backward and forward movement on the plunger 1, Figs. 1, 2, is a rider 4 carried by the arm 5, the rider having a beveled rear face 6 on which the staple rides after it is formed and during the time that it is fed downward to the work. This rider is pressed rearwardly by the spring 7 at the proper time by means not shown, and which forms no part of this invention to bring its arm 5 substantially in line with front plate 8 to receive the staple.

The plunger 1, Fig. 2, also carries at its lower end a staple carrier 9 having a horizontal slot 10 therein into which the wire thread 11 is automatically fed through the guide 35, and held while the legs are formed, as will be described.

The carrier 9 is thrust forward slightly by the spring 12 at the proper time to position the staple on the rider and the staple legs in the guides by means not shown, and not material in this application.

My novel work positioner and staple or thread guide, comprises a plate 13, Figs. 3, 4, with a staple leg forming shoulder 14 near its rear edge. In order to insure the leading of the wire thread freely into the

hole prepared therefor, I provide the guide 13 with a needle or leader adapted to enter and thus to position the work and subsequently to lead the thread or staple leg thereinto. To this end the member 13 is provided on its rear or inner face 15 with a groove 16 Fig. 5, in which the staple is positioned by the carrier 9 and by which it is guided to the work.

10 The plate 13 is cut away on its front face to form a depressed area 17 to receive a suitable resilient member as a spring 18 which acts normally to retain in extended position, see Figs. 3, 4, the yielding work positioner and disappearing staple leg leader 19 which slides vertically in a slot 20 and which has at its outer end a combined work positioning and staple leg leading or guiding point 21. There are two of these plates 15, 13^a, one on each side of the plunger, Fig. 1, each provided with a guiding point 21.

15 Beneath the head 1, Fig. 1, is a post 23 carrying a base 24, with a plate 25, and recessed at 26, Fig. 2, in which the staple or loop is positioned to be acted upon by the anvil.

20 The anvil comprises two disappearing triangular members 27 pivoted to the member 24 at 28 and adapted to be forced upward by links 29 actuated by suitable mechanism, not shown, so that the faces 31 of the anvil will lie in the same horizontal plane and engage the work at its lower or under side. 25 The post 23 may be adjusted as to height for convenience and carries guides 30 which are also adjustable.

25 While my novel guide may be used with advantage in any case where it is desired 40 to drive a staple into a piece of material at a predetermined point, it is, as stated, particularly valuable where it is desired to staple or stitch a piece of non-staple-penetrable material to a second piece of non-staple-penetrable material, as metal, or to a piece of staple penetrable material. I have found the same particularly useful for stapling leatherboard or the like shoe shanks to steel reinforcing members such as are 45 shown in Fig. 6 which is a plan of such member, the body or base being shown at 32, the reinforcing member of steel at 33, perforated at 34, the staple shown as having been applied thereto.

50 In use the operation of my invention is as follows, beginning with the movements of the parts just following the application of a staple. At this moment the point 21 of the work positioning, and staple leading member 19 will be just above the anvil 27, and the rider 4 will be just to the left of the point 21.

55 As the point 21 rises the rider 4 is fed rearwardly beneath the point 21 until, when

the latter reaches its limit of upward travel 65 and somewhat above the position shown in Figs. 1, 2, the rider is so positioned that the upper edge of the bevel face 6 is just beneath the point 21. At this time the wire thread 11 Figs. 1, 2, is automatically fed 70 from a spool, not shown, through the guide 35 and slot 10 until its end projects as shown in Fig. 1. The plunger 1 then begins its downward travel, carrying with it the rider 4.

75 At once the cutter 3 on the left hand side of the machine, Fig. 1, severs the wire at the proper point and shoulders 14 on the guide 13 and 13^a, Fig. 3, engage the opposite extended ends of the severed wire and bend 80 them down at right angles to the portion which remains in the slot 10 and which forms the head of the staple.

85 The carrier 9 is now thrust forward and the staple is positioned so that its two legs are received by the grooves 16 in the guides 13, 13^a, and straddling the rider 4, near the top of the bevel face 6.

90 As the plunger 9 travels downward with its rider 4 the latter gradually is withdrawn from beneath the staple toward the left, Fig. 2, the top of the staple meanwhile riding downward on the bevel face 6, beneath the end of the hammer which is slotted to receive the head of the staple. Just before 95 the work is reached the parts occupy the positions substantially as shown in Fig. 2.

95 In the meantime the work has been positioned by the operator beneath the staple leading members 19 and the points 21 inserted into the previously prepared holes which are to receive the respective legs of the staple.

100 For convenience I have shown, Fig. 2, the lower end of one leg 36 as depending slightly below the point 21, as it might or might not be in practice according to the adjustment of the machine for producing a leg of certain length.

105 Obviously the two legs of the staple will now be directed along the grooves 16 the length of the leaders 19 accurately into the holes 34 in the reinforcing member 33 and as the staple is fed downward the anvil members 27, which meantime are forced up 110 by their links 29, engage the lower face of the work and the staple legs are turned up against the bottom of the work by contact therewith of the upper faces 31 of the members 27. As the staple leading members 19 engage the work on the anvil 27 they yield upwardly against the springs 18 until they disappear and are on a level with the lower edge of the member 13 thus avoiding all danger of their being crushed between the 115 work and plunger.

120 As the points 21 disappear upwardly within the members 13 and 13^a the lower

edge of the rider 4 slides out from beneath the staple so that the plunger can press it firmly against the goods. The operation is then repeated as described. The rider 4 gives sufficient support to the staple so that it can be driven through the goods 32 which are of staple penetrating material.

My novel shank comprises a body 32 of suitable material, as leatherboard, pasteboard, etc., and a reinforcing member 33 of any desired material having the required strength and yielding quality, as spring metal.

While metal reinforcing members have been used by tacking their ends to the shank body, this construction has proven unsatisfactory because under existing factory conditions, it has been impossible to tack their ends securely enough to insure their remaining in position within permissible cost limits. In other words the cost of so doing prevents their use in competition with other forms of shanks.

It has been impossible to staple them as illustrated because there was no known method of, nor machine for so doing. The reinforcing member must first be provided with holes for the staple and the latter must then be applied to the shank and reinforcing member at a cost that will permit the use of the shank in competition with others, even though of inferior quality.

By stapling the two members intermediate their ends as illustrated they are securely fastened, against either lateral or longitudinal displacement, and a superior shank is produced at a commercially usable cost.

Wooden reinforcing members will not answer the purpose of metal members as they are too clumsy to be used in any but the cheapest shoes and the wood soon loses its resiliency.

While I have described one embodiment of my invention, I do not wish to be limited to the precise details thereof beyond the terms of the specification and claims.

Claims:

1. In a wire stitching machine, means for feeding the thread, thread severing means, means for forming the severed thread into a staple, staple leg leaders, guides for the staple legs adapted to lead them into said leaders, the leaders movable relative to the guides to lead the staple legs to predetermined points in the work, and then retreat from the staple legs as they enter the work, and staple forcing means.

2. In a wire stitching machine, means for feeding the thread, thread severing means, means for forming the severed thread into a staple, staple leg leaders, guides for the staple legs adapted to lead them into said leaders, the leaders movable with the sta-

ples to lead the staple legs to predetermined 65 apertures in non-staple perforable work and to retreat and expose the staple legs as they enter the work, and staple forcing means.

3. In a wire stitching machine, staple 70 forming means, staple setting means, guides for the staple legs, and work positioning and staple guiding points carried by said guides adapted to enter apertures in the work and to be retracted within the guides. 75

4. In a wire stitching machine, staple 80 forming means, movable guides for the staple legs, and yielding staple leg guiding points carried by said guides adapted to enter apertures in the work and guide the staple legs thereinto.

5. In a wire stitching machine, means for feeding the thread, thread severing means, means for forming the severed thread into a staple, traveling guides for the staple legs, 85 having relatively movable staple leg leaders to travel in the guides and into the work with the staple legs and then withdraw from the work.

6. A staple guide comprising plates with 90 movable guides for the staple legs, and yielding staple leg leaders carried by the guides to guide the staple legs to points on the work.

7. A staple guide comprising plates having 95 staple guiding means thereon, staple guiding points carried by said plates adapted to enter apertures in non-staple penetrable work and guide the staple legs thereinto, and means to permit the staple leg guiding points to be retracted within 100 said plates.

8. A staple guide comprising a plate with staple guiding means thereon, and a spring pressed staple leg leader movable relative thereto to receive the staple leg therefrom and to enter the work and lead the staple leg thereinto. 105

9. A staple guide comprising plates with 110 staple leg guiding means, means for forcing the guiding means toward the work, and yielding staple leg leaders on said guiding means to lead the staple legs into the work and subsequently withdraw therefrom.

10. A staple guide comprising plates with 115 staple guiding means thereon, and movable staple guiding leaders on said means adapted to receive the legs of the staple at their ends, guide the staple ends to the work, and retire within the plates while the staple is entering the work. 120

11. A staple guide comprising a plate with staple guiding means thereon and a staple leg leader movable in the plate with the staple through part of its travel only.

12. A staple guide comprising a plate with 125 staple guiding means therein, and a relatively movable staple leading member adapted to receive the staple near the upper end

of the member and guide the staple to the work, and retire within the plate while the staple is entering the work, and a spring acting normally to hold said leading member 5 in outward position.

13. A staple guide comprising the members 13, 13^a, grooves 16 therein, staple leg

leaders 19 movable in said plates, springs 18 for said staple leg leaders, the latter having the guiding points 21 thereon.

In testimony whereof, I have signed my name to this specification.

ALFRED M. MOORE.
